UNITED STATES PATENT OFFICE

JAMES S. THOMPSON, OF NEW ROCHELLE, NEW YORK, ASSIGNOR TO FIREBAR CORPORATION, OF CLEVELAND, OHIO, A CORPORATION OF DELAWARE

GRATE BAR

Application filed November 17, 1931. Serial No. 575,535.

This invention relates to grate bars of the type used in locomotives, boiler furnaces, and for other heavy duty purposes and is concerned more particularly with a novel grate bar which is of extremely light weight, low cost, and long life. In many respects, the new grate bar resembles that disclosed in my co-pending application, Serial No. 546,778, filed June 25, 1931, but is an improvement thereon in certain details of construction which add to the durability of the bar and increase its resistance to distortion, warping, etc. resulting from the temperatures to which it is exposed in operation.

The new bar comprises a carrier of any suitable construction provided with trunnions and a shaker arm, and a plurality of fuel-supporting units or fingers mounted detachably on the carrier across the latter and free to move angularly relative to the carrier to a limited extent. These units are of sheet metal and preferably made of a single steel blank, the latter being shaped by a series of forming operations to produce a hollow plate-like article having a recess in its bottom, in which the carrier is received, and a fuel supporting top. The top and side faces of the unit are formed with irregularities which prevent cumulative expansion effects and these irregularities may be so arranged as to provide wide and uniform distribution of air to the fuel carried by the unit.

As a further feature, the unit is constructed to make it self-cooling by induced circulation of air through its interior and, for this purpose, the unit is provided with openings at or near its lower end which permit cold air from below the grate to enter the interior of the unit, and other openings at a higher level through which the air may escape. These openings are so formed and disposed as to prevent their being clogged with ashes and, as the air from the ash pan flows upward to the fuel bed, a portion of it enters the chamber within the unit near the bottom thereof and passes out near the top, the temperature of the unit causing continuous air flow through it. The entrance openings in the unit also act as a drainage means for the chamber in

the event that water enters the chamber when the ash pan is being cleaned out by hosing.

For a better understanding of the invention, reference may be had to the accompanying drawing, in which

Fig. 1 is a view illustrating a carrier bar in cross-section with a fuel supporting unit thereon shown in elevation, parts of the unit being broken away; and

Fig. 2 is a fragmentary view showing a portion of the carrier with two units thereon shown in end elevation.

In the embodiment of the invention illustrated the grate bar comprises a carrier which includes a web 11 having a central up-standing flange 12 on its upper face and a strengthening rib 13 extending along the under side of the web. The carrier is provided at its ends with trunnion arms 14 provided with trunnions 15 and the carrier may be rocked on its trunnions by a shaker arm 16 extending downwardly from its under surface and adapted to be connected to a shaker rod by which a group of carrier bars in the grate may be shaken in unison.

The fuel is supported on the carrier on the top of a plurality of fuel supporting units generally designated 17. Each of these units is made of sheet stock, such as sheet steel of a relatively light gauge. The units may be made of a pair of blanks properly formed and provided with defining flanges, the two halves of the complete unit being connected with their flanges in registry, or each unit may be formed of a single sheet metal blank as described in my co-pending application above identified. The one piece unit is preferred.

Each unit as illustrated is provided in its lower edge with a recess of a shape generally similar to the cross-section of the carrier so that the unit can be mounted on the carrier edgewise, and the recess is of somewhat greater dimensions than the carrier so that the unit is free to move angularly relative to the carrier to a limited degree when the carrier is rocked. Ordinarily, the unit rests on the flat surfaces 18 on either side of the flange and the angular movement of the unit relative to the carrier is limited by engagement

of one or the other of the lugs 19 on the unit at the mouth of the recess with the under side of the web 11.

The unit illustrated is made of a single blank of sheet metal and it has a solid top which is formed with irregularities which prevent the expansion of the top from being cumulative. The side walls of the unit are similarly provided with irregularities to prevent cumulative expansion effects and the irregularities in the top and side walls also stiffen and strengthen these parts.

In the construction shown, the side walls are provided with a plurality of vertically extending lugs 20 formed by shaping the metal outwardly, and the lugs partly define air passages 21 between them for upward flow of air along the side faces of the unit. Extending across the air passages are stiffening and strengthening beads 22, these beads extending outwardly from the face of the unit a less distance than the lugs 20 and thus not interfering with the upward flow of air between the lugs to a substantial degree.

The top of the unit is provided with a plurality of small projections 23 which are separated by air channels 24 and air flowing up through the passages 21 enters the channels and is distributed over the top of the unit to the fuel supported on the projections.

By forming the top with a multiplicity of projections, this portion of the unit is made strong and rigid and the total expansion of the top from end to end due to the temperature of the fuel bed resting thereon is not cumulative. Some portions of the top expand horizontally while other portions expand in a generally vertical direction and the consequence is that the exposure of the top to working temperatures does not result in the top becoming warped or bulged. Similarly, the formation of the side walls of the unit with the projections and beads strengthens these walls and permits the unit to be made of lighter stock. These walls are in compression under the load of the fuel bed when the unit is in service and if it were not for the use of such irregularities, the side walls might bulge and buckle. The strengthening of the side walls of the unit by the means described also provides for a wide distribution of air to the fuel so that more rapid and complete combustion is obtained.

In the one piece unit the side walls may constitute downward extensions from the top, with each side wall having edge flanges 25 which meet and are joined by a line of welding 26. Where the unit is made of two parts, these parts are preferably of dish shape and provided with edge flanges which are placed in contact and then connected by a line of welding.

When the unit is in service the top is in contact with the burning fuel while the bottom lies at a substantial distance below the

fuel bed and is kept at a much lower temperature than the top by the relatively cold air which is flowing upward from the ash pan through the grate to the fuel bed. In order to equalize the temperature within the unit and prevent localized heating, I have constructed the new unit so as to obtain air circulation.

For this purpose, the unit is provided with air entrance openings 27 at or near the bottom thereof and air exit openings 28 near the top. The openings 27 are preferably formed along the seam in the lowermost portions of the unit on opposite sides of the recess in which the carrier is received, although if desired, entrance openings 27' formed in the opposite faces of the unit may be used in substitution for or in combination with the openings 27. Similarly openings 28 are preferably in the edge of the unit but if desired the faces of the unit may be formed with openings 28' preferably in the outermost air channels 21. Openings 28 and 28' may be used alternatively or in combination. When the openings are formed in the seam, the two edges of the blank may be shaped as indicated at 28a, Fig. 2, so that the openings are completed when the edges are placed in contact in the shaping operations. The disposition of the openings in the manner illustrated prevents the openings from becoming clogged with ashes, the openings 28 being protected by overhanging portions of the unit and the openings 28' lying below strengthening ribs 22.

In the unit constructed as described, air flowing up from the ash pan is induced into the interior of the unit through the bottom openings by the draft through the unit created by the heating of the top thereof, and the cold air flows through the central chamber and passes out through the top openings, thence flowing upwardly between the ends of units on adjacent cross bars to the fuel bed. The bottom openings are kept clear of ash since they lie beneath the main body of the unit or in the sides thereof and the top openings are similarly protected by the slightly overhanging top of the unit. Since the openings are small, only fine ash could enter the top openings in any event and such ash would pass down along the sloping edge of the unit and pass out through the bottom openings so that the interior of the unit will not become filled. The bottom openings also serve for drainage purposes as above pointed out, and since they are in the lower parts of the unit, water used in cleaning the ash pan cannot collect and be retained in the unit.

What I claim is:

1. A grate bar which comprises a carrier and a plurality of fuel-supporting units mounted transversely thereon, each unit comprising a sheet metal body resting edgewise on the carrier and containing a large central

chamber, said body having a recess in its lower edge for reception of said carrier and said chamber having an opening near its lower end for admission of air into said chamber, and an opening near its top for escape of air from said chamber.

2. A grate bar which comprises a carrier and a plurality of fuel-supporting units mounted transversely thereon, each unit comprising a sheet metal body resting edgewise on the carrier and containing a large central chamber, said body having a recess in its lower edge for reception of said carrier and said chamber having an opening in its edge near the bottom of said body for admission of air into said chamber and an opening near its top for escape of air therefrom.

3. A grate bar which comprises a carrier and a plurality of fuel supporting units resting edgewise on said carrier and extending transverse thereto, each unit comprising a body of sheet metal containing a large central chamber and being formed with a recess for reception of said carrier, the body having an edge seam along at least its side and bottom edges, said seam being provided with an opening near the bottom of the chamber for admission of air, and an opening near the top of the chamber for escape of air.

4. In a grate bar, a fuel supporting unit of sheet stock having a recess open at its lower edge for reception of a carrier bar and having a central chamber coextensive with said unit, said chamber having an air inlet opening through the chamber wall near the bottom of the unit and an air outlet opening through the chamber wall near the top of the unit.

5. In a grate bar, a fuel supporting unit of sheet stock having a recess open at its lower edge for reception of a carrier bar and having a central chamber co-extensive with said unit, said unit having an opening in its edge at its lowest point for admission of air into said chamber and an opening in its edge near its top for escape of air from said chamber.

6. In a grate bar, a fuel supporting unit of sheet stock having a recess for reception of a carrier bar and having a central chamber co-extensive with said unit, said unit having an edge seam along at least its side and

bottom edges formed to provide an opening near the bottom of the unit for admission of air into said chamber and an opening near the top of the unit for escape of air from said chamber.

70

7. In a grate bar, a fuel supporting unit of sheet stock having a recess for reception of a carrier bar and having a large central chamber, the wall of said unit having an opening near the bottom of the unit for admission of air into the chamber and an opening near the top of the unit for escape of air from the chamber.

75

8. In a grate bar, a fuel supporting unit having a recess in its lower edge for reception of a carrier bar, said unit being hollow and formed of sheet stock and having a pair of openings in its lowest portions one on each side of said recess for admission of air into the hollow interior of the unit, and a pair of openings one on each side of said recess and near the top of the unit for escape of air.

80

9. In a grate bar, a fuel supporting unit having a recess in its lower edge for reception of a carrier bar, said unit being hollow and formed of sheet stock, said unit having a pair of openings in its edge in its lowest portions, one opening on each side of said recess, for admission of air into the interior of said unit, and a pair of openings in its edge near its top, one opening on each side of said recess, for escape of air from the interior of the unit.

85

10. A grate bar which comprises a plurality of fuel-supporting units, each having an opening for reception of a carrier, and a carrier received in the openings in said units, each unit being hollow and having openings near its bottom on opposite sides of said carrier for admission of air into its interior and openings near its top on opposite sides of said carrier for escape of air.

90

11. In a grate bar, a fuel-supporting unit having an opening for reception of a carrier bar, said unit being hollow and having air admission openings near its bottom and on opposite sides of said carrier bar openings, and air outlet openings at its top on opposite sides of said carrier bar opening.
